UNITED STATES PATENT OFFICE.

GEORGE C. McCLELLAN, OF MENA, ARKANSAS.

BORING-MACHINE.

SPECIFICATION forming part of Letters Patent No. 670,003, dated March 19, 1901.

Application filed June 2, 1900. Serial No. 18,884. (No model.)

To all whom it may concern:

Be it known that I, GEORGE C. McCLELLAN, a citizen of the United States, residing at Mena, in the county of Polk and State of Arkansas, have invented a new and useful Boring-Machine, of which the following is a specification.

My invention relates to mortising-machines, and more particularly to that class of machines used for cutting mortises in the sides of window-frames for the attachment thereto of the pulleys for the sash-cords.

One object of my invention is to produce a machine which can be easily adjusted for use upon the different-sized frames and which can be easily adjusted as to the depth to which the mortise is to be cut.

Another object is to provide a convenient means by which the mechanism can be withdrawn from the frame after the mortise has been made.

With these objects in view my invention consists in the improved construction and novel arrangement of parts of a mortising-machine, as will be hereinafter more fully set forth.

In the accompanying drawings, in which the same reference-numerals indicate corresponding parts in each of the views in which they occur, Figure 1 is a perspective view of my improved mortising-machine. Fig. 2 is a front view of the same. Fig. 3 is a sectional view near the top looking downward; and Fig. 4 is a bottom plan view, the adjusting mechanism being shown in two positions.

Referring more particularly to the drawings, 1 indicates the base of my machine, which is preferably formed from wood and may be of any convenient size and shape. The forward end is provided with a central slot or recess 2, from each side of which rises a vertical standard 3, preferably circular in cross-section. A cross-piece 4 is secured to the upper ends of said standards and is provided with a suitable catch 5. A frame 6 is arranged to slide vertically upon said standards by means of perforated brackets or ears 7, which fit loosely upon the standards. The upper end of the frame is preferably formed substantially circular or bow-shaped and is adapted to engage with the catch and be held in its raised position. Two cross-heads 8 are secured to the bottom and intermediate cross-

pieces 9, respectively, on the frame, and are joined at their ends by vertical rods or braces 55 10. Journaled in the cross-pieces is a series of rotary shafts 11, five being shown in the drawings, the upper ends of which are provided with intermeshing gears or pinions 12. One of the shafts, preferably the central one, 60 is extended above the others and is provided with a bevel-gear 13, to which motion is communicated from a corresponding bevel-wheel 14 on the shaft 15, which is journaled transversely at the upper end of the frame. The 65 outer ends of the shaft are provided with the usual crank-arms 16 for rotating it, and also with a pinion 17, which is adapted to engage with a rack 18 for raising the frame after the mortise has been formed. The rack 18 is 70 preferably swiveled to one of the standards by means of collars 19, the upper one of which rests upon a shoulder 20, formed upon the standard, and prevents the rack being moved downward, but permits of its being freely 75 swung around upon the standard.

The lower end of each of the shafts 11 is provided with any suitable chuck 21, within which is secured the stem or shank of a bit 22—as, for instance, by means of a set-screw 80 23. Although the bits may be of any desired construction I have good results by using double-lipped screw-center bits. Owing to the reverse motion communicated to said shafts by the intermeshing gear-wheels a portion of said bits must be left-handed, as they will run in a reverse direction to the others. The end bits are shorter than the central ones, so that they will pass part way through the frame when the central bits have passed 90 entirely through, thereby forming a seat at each end of the mortise for the reception of lips or projections upon the wheel-casing to be secured therein. A suitable collar 24 is adjustably secured upon the lower end of one 95 of the standards—as, for instance, by means of a set-screw 25, against which the lower end of the bit-frame will engage and prevent its farther downward passage.

For the purpose of adjusting the machine laterally upon the frame to be mortised I provide the base with two rods or bars 26, which project from the bottom thereof in position to engage with the side of the frame being operated upon and hold the machine in the proper position to cut the mortise. The bars

are pivotally secured at their ends to the outer ends of two sets of swinging arms 27, the inner ends of said arms being pivotally secured near the center of the base. Pivotally connected with the forward arms intermediate their ends are two links 28, which are adapted to fit within suitable recesses 29, formed in the bottom of the base. The forward end of each link is provided with a screw-threaded boss or projection 30, into which fits an adjusting-screw 31. The projection and screw fit within a vertical slot 32 through the base, and the adjusting-screw is provided with a shoulder 33, which engages with a plate 34 on top of the base and clamps the lower end of the link, which is preferably expanded, as shown at 35, against the bottom of the base and holds the swinging arms and the adjusting-rods rigidly in position.

20 In using my improved mortising-machine the rods upon the bottom are adjusted so that when the base is placed upon the frame the rods will pass down upon the sides thereof and hold the base against lateral movement.

25 The bit-frame is then released from the catch at the top, when its own weight will carry it down until the bits pass through the slot in the forward end of the base and engage with the frame to be mortised. The shaft at the 30 top of the frame is then rotated, which will impart motion to the bits. As soon as the bits have entered the wood the desired distance the lower end of the frame will engage with the adjusting-collar and prevent the further descent of the frame. The operator then 35 swings the rack around until it engages with the pinion, when the frame can be readily withdrawn to its original position by simply rotating the shaft with one hand.

40 Having thus fully described my invention, what I claim as new, and desire to secure by Letters Patent, is—

1. In a mortising-machine, the combination, with a base provided with a slot at one end, of standards rising from the base upon opposite sides of said slot, a cross-piece at the upper ends of said standards provided with a catch, a frame mounted upon said standards, the top of which is curved and adapted 45 to engage with the catch, cross-heads secured to the cross-pieces of the frame, rods for securing the ends of said cross-heads together, shafts journaled in said cross-heads, the upper ends of which are provided with intermeshing gear-wheels and the central one is provided with a bevel gear-wheel, a shaft journaled in the frame above said gear-wheels, the ends of which are provided with cranks and the intermediate portion is provided with 50 a bevel-wheel in position to engage with the bevel-wheel on said shaft, bits removably secured at the lower ends of said shafts, the outer ones of which are shorter than the inner ones, a collar adjustably secured upon 55 one of the standards below the frame, and means for moving the frame vertically upon said standards, substantially as described.

2. In a mortising-machine, the combination, with a base, one end of which is slotted, of two cylindrical standards rising from said base upon opposite sides of the slot, the upper end of one of which is provided with a shoulder, a cross-piece at the upper end thereof provided with a catch, a frame, the sides of which are provided with sleeves that fit 70 loosely upon said standards, shafts journaled in the frame, the upper ends of which are provided with intermeshing gear-wheels and the lower ends with chucks, a shaft journaled in the upper portion of the frame provided 75 with means for operating said shafts, a gear-wheel upon said crank-shaft adjacent to one side of the frame, a rack adjacent to said gear-wheel, the ends of which are provided with collars which fit loosely upon the standards, the upper collar resting upon the shoulder of said standards, and a collar adjustably secured to the other standard below the frame, substantially as described.

3. In a mortising-machine, the combination, with a base, one end of which is slotted, of standards rising from the base upon opposite sides of the slot, a bit-frame upon said standards provided with means for operating the same, swinging arms pivotally secured to 90 the under side of the base, bars pivotally secured to the outer ends of said arms, and means for securing said arms and bars in their adjusted positions, substantially as described.

4. In a mortising-machine, the combination, with a base, one end of which is slotted longitudinally, of a bit-frame arranged above the slotted end of the base and provided with means for operating the same, two pairs of 105 swinging arms pivotally secured to the under side of said base, a bar pivotally secured to the outer end of each pair of arms, a link connected with one arm of each pair intermediate its ends, and a clamping-screw extending through the base and engaging with each link, substantially as described.

5. In a mortising-machine, the combination, with a base, one end of which is slotted and provided with plates, of a bit-frame 115 above said slotted end of the base and provided with means for operating the same, two pairs of swinging arms pivotally secured to the under side of the base, a bar pivotally secured to the outer end of each pair of arms, a link pivotally secured to the intermediate portion of one arm of each pair, the opposite end of which is expanded and provided with a screw-threaded boss, and a shouldered screw extending through each slot, the lower end of 120 which engages with the boss and the shoulder engages with the plate and is adapted to force the expanded portion of the link into engagement with the base and lock the bars in their 125 adjusted positions, substantially as described.
